UNITED STATES PATENT OFFICE.

PAUL S. MACMICHAEL, OF SEATTLE, WASHINGTON, ASSIGNOR TO GLADDING, McBEAN & CO., OF SAN FRANCISCO, CALIFORNIA, A CORPORATION OF CALIFORNIA.

ROOFING.

Application filed August 30, 1926. Serial No. 132,477.

This invention relates to weather strips for roofing.

In covering roofs with shingles of tile, slate, or other material, the practice has been 5 to render the roof water-tight by laying the shingles in courses in such a manner that at all parts of the roof area there were not less than two layers of shingles between the exposed upper surface of the shingle assembly and the roof sheathing in order that all exposed vertical joints could be underlaid with respect to the upper or unexposed end of another course of shingles, for the purpose, mainly, of providing water conducting 10 gutters at the interstices between the adjacent shingles of each course.

The roofing system above outlined is suitable where relatively thin tapering shingles are employed; but with thicker shingles having little or no taper—as flat tile, for example—such a method is objectionable on account of the quantity of material required to lay the roof by this method.

The object of my invention, generally 25 stated, is to provide a light-weight, inexpensive, easily applied and efficient device which may be used in lieu of a large proportion of shingles which have hitherto been requisite in the laying of a water-tight roof.

More specific objects and advantages of 30 the invention will appear in the following description.

The invention consists in the novel construction, arrangement and combination of 35 parts hereinafter described and claimed.

In the accompanying drawing—

Figure 1 is a top face view of a portion 40 of a tile roof embodying the present invention; Fig. 2 is a longitudinal vertical section taken on line 2—2 of Fig. 1; Fig. 3 is a detail sectional view on line 3—3 of Fig. 2, the upper course of tile being omitted from Fig. 3; and Fig. 4 is a perspective view 45 of the weather strip which is utilized in the preceding views.

Fig. 5 is a view similar to Fig. 2 illustrating a modified construction of roof; and Fig. 6 is a perspective view of the weather strip used in the roof construction illustrated in 50 Fig. 5.

Referring first to Figs. 1 to 4, inclusive, 10 represents roof boards which are secured in a well-known manner to the framework (not shown) of a roof structure; and 11 represents roof paper, or an equivalent, which is

customarily employed upon the upper surface of a roof board assembly.

12, 12¹ and 12² represent shingles or tile, as they will hereinafter be designated, of three roof-courses. The tile shown in Figs. 60 1, 2 and 3, being of the type which is conventionally known as flat tile, each being of a substantially rectangular shape and of substantially the same thickness throughout.

The tile of the respective courses are laid 65 in side by side relation with relatively narrow spaces 13 therebetween. The tile of each succeeding course, after the first course, are laid to slightly overlap the tiles of the course next before laid. In accordance with 70 the present invention such overlapping portions are insufficient to bridge the distance between the lower edge, as 14, of a superposed course and the upper edge, as 15, of the next lower course; in other words, there 75 is space between the lower and upper edges 14 and 15, respectively, of the alternate courses of tile.

The tile in the successive courses, however, 80 are laid in a manner to break joints with each other—that is to say, to have the interstices 13 of each course outside of the planes of tile interstices of the courses next above and below the respective course.

For each of the interstices between ad- 85 jacent tile of every course thereof, I provide a weather strip (see Fig. 4) comprising a strip of sheet metal, preferably copper, which is pressed or otherwise formed with a cross section of substantially the shape of 90 an inverted capital letter T to provide a central ridge 17 with laterally protruding flanges 16.

The flanges 16 are grooved or corrugated to provide in the upper surface of each 95 flange one or more gutters, two being shown, which are indicated by 18 and 19, respectively.

The ridge 17 and the gutters 18 and 19 extend longitudinally of a weather strip for 100 the entire length thereof or nearly so.

For use with flat tile, as shown in Figs. 1 to 3, a weather strip is provided at an end of each with upwardly directed lugs 20, constituting hook elements to engage against 105 the upper ends of the tile which are seated upon the respective flanges.

Thus arranged, the ridge 17 of a weather strip extends upwardly into the interstice between the proximate side edges of the tile 110

and serves to prevent lateral displacement of the weather strip with respect to the tile which are thereby supported.

In practice, the tile are laid in approximately horizontal courses, beginning with the lower course of tile 12. The roofer disposes the tile and weather strips alternately, nailing each tile in place and hooking each weather strip over the upper edge of the tile.

10 The weather strips and tiles 12¹ of the next course are next placed in overlapping relation with the tile of the first laid course and the tile 12¹ secured by nails, the weather strips and tiles 12² are then laid, and so on 15 with each succeeding course until the weather strips and the tile for the entire roof area are laid. The nails for securing the tile are represented by 21 in Fig. 1.

In Fig. 5 I show a modified form of tile, 20 denoted by 120, 120¹ and 120² for the respective courses of a roof. The individual tile being characterized by each having along its upper edge a downwardly extending flange 23 which is engageable with one of a series 25 of cleat elements 22 provided therefor on the roof structure.

For the flange type of tile shown in Fig. 5, the weather strips are similar to those explained above for the flangeless type of tile 30 except that the lugs or flange extensions, denoted by 20¹, are turned downwardly into engageable relation with the roof cleats 22, see Fig. 5, which retain the tile in place.

It is to be noted that the tile are secured 35 to a supporting roof frame structure; as, for example, by means of nails 21 (Fig. 1) or by means of flanges 23 (Fig. 5) formed upon the tile, engaging roof cleats 22.

The weather strips, however, are connected either to the tile directly or to the cleat to which a tile is coupled, the purpose being to simply retain the weather strips in operative relations with the tiles pertaining thereto.

45 It is also to be noted that my improved

weather strips serve not only to close the interstices between the tile of each course thereof, but also to bridge the intervals between spaced apart alternate courses of tile. The grooved flange elements 16 of my improved weather strip extend below the associated tile of the respective courses to afford gutters for conveying away any water entering the interstices between the tile. The ridge 17 of a weather strip is of less height 50 than the thickness of a tile and by locating the flanges entirely below the tile of the respective courses, the weather strips are hidden from view and do not render a tile roof unsightly. 55

The term "tile" as hereinbefore employed is not intended to limit my invention for use with a clay product exclusively, as it may be advantageously employed with slate and other kinds of shingles. 60

What I claim, is,—

1. A weather strip for a shingle roof comprising a metal strip consisting of a transversely folded sheet of metal having a longitudinally extending laterally folded ridge 70 and two laterally disposed flanges longitudinally grooved, and having at one end, lugs projecting at right angles to the planes of the flanges, adapted to engage the upper edges of the shingles. 75

2. A weather strip for a shingle roof embodying a struck up metal strip having a longitudinally folded ridge, adapted to extend upwardly between the adjacent edges of two shingles on tiles and having laterally 80 projecting flanges, longitudinally corrugated to form gutters, and formed with end flanges bent perpendicularly to the plane of the corrugated flanges and adapted to abut against the ends of the shingles at the side of the 85 central ridge of the strip.

Signed at Seattle, Washington, this 12th day of August 1926.

PAUL S. MACMICHAEL.
